UNITED STATES PATENT OFFICE.

VINCENT BENDIX, OF CHICAGO, ILLINOIS.

ENGINE STARTER.

Application filed October 12, 1916. Serial No. 125,292.

To all whom it may concern:

Be it known that I, VINCENT BENDIX, a citizen of the United States, residing at Chicago, in the county of Cook and State of Illinois, have invented certain new and useful Improvements in Engine Starters, of which the following is a specification.

My invention relates to a starter for an engine such as a gas engine, and the object 10 thereof is to provide a simple, efficient and reliable device of this character to be operated by a prime mover of any kind, such for instance as an electric motor.

My starter embodies as a material part of 15 its organization that type of drive or transmission exemplified in patents heretofore issued to me, for instance Patent No. 1,125,935, dated January 26, 1915, and Patent No. 1,172,864, dated February 22, 1916. 20 This type of engine starter is characterized by a prime mover, such as an electric motor, and a transmission or drive for transmitting the power of the motor by means of a rotatable member, such as a screw shaft, and 25 a driving member such as a pinion mounted thereon, for transmitting the power of the motor to some member or part of the engine to be started, such as the fly-wheel thereof.

The object of my present invention is 30 to provide simple and efficient means for preventing any possible creeping movement of the pinion on the screw shaft due to vibration of the automobile on which my engine starters are commonly employed, such means 35 being arranged to prevent any possible slight rotation of the pinion which might advance it into contact with the fly-wheel and thereby cause a clashing and a rasping sound. These means are so designed as not to interfere 40 with the ordinary or normal operation of the drive.

In the drawing Fig. 1 is an elevation of 45 my drive illustrating a portion of the electric starting motor and a portion of the fly-wheel of the engine to be started; Fig. 2 a plan view of a portion of the drive consisting of the pinion, a portion of the screw shaft, and the means for preventing creeping movement of the pinion, and Figs. 3, 4, 50 5, and 6 are detail views illustrating different forms of such means.

The general construction of the drive is the same as that shown in my patents aforesaid and therefore it will be sufficient to 55 say that the same comprises in connection

with the extended armature shaft 1, the rotatable hollow screw shaft 2, the pinion 3 adapted to mesh with the teeth 4^a of the fly-wheel 4, the coiled spring 5 constituting the driving connection between the collar 2^a 60 of the screw-shaft and the collar 6 secured to the armature shaft and the bolts 7, 8 which anchor the ends of the spring.

Referring to Figs. 1 and 2, the means provided to prevent possibility of rotation or 65 creeping movement of the pinion 3 consists of a spring 9 of rather light construction and preferably of the form shown in Fig. 1, according to which such spring is a bent wire with one end anchored underneath the 70 head of the bolt 8 and extended outwardly therefrom in a long curve towards the outer edge or periphery of the weight disk 3^a of the pinion 3, the extreme outer end 9^a being outwardly and upwardly bent or turned, as 75 shown in Fig. 1, and the outer portion thereof being turned angularly to one side with respect to the remaining portion of the wire, as indicated in Fig. 2 so that weight shall 80 strike the wire at an angle.

Describing the operation and assuming that the pinion 3 is on its return to home position, shown in full lines, from its meshed position, shown in dotted lines, the periphery of the weight disk 3^a will come in contact 85 with the outer free end portion of the spring 9 which will finally catch over such periphery, as indicated in Fig. 1, whereby the pinion will be held to its home position with a sufficient pressure or force to prevent any 90 possible rotary movement due to vibration and consequent longitudinal movement along the screw shaft. However, this pressure or force is not such as to prevent a proper or normal operation of the drive, inasmuch as 95 it is not sufficient to hold the pinion back as against a positive longitudinal movement thereof caused by the rotation of the screw shaft by means of the electric motor.

Referring to Figs. 3 and 4, the spring is 100 in the form of a flat band 10 reversely curved and anchored in the same manner as the spring 9 and also having its outer end shaped as shown at 10^a, in order that the corner 3^b, which is the high point of the weight 3^a, 105 shall not catch upon the spring but strike it at an angle. In Figs. 5 and 6 the spring 11 has a bend 11^a.

In both forms of construction, the spring 110 is independent of the pinion when the latter

is in driving position and cooperates therewith only when it is in non-driving or home position.

I claim:

6. 1. In a device of the character described, the combination of a rotatable member, a driving member mounted thereon for rotary movement therewith and longitudinal movement thereof, and means mounted on such 10 rotatable member and acting on said driving member to prevent creeping movement of the latter.
15. 2. In a device of the character described, the combination of a rotatable member, a driving member mounted thereon for rotary movement therewith and longitudinal movement thereof, and retarding means mounted 20 on said rotatable member and independent of the driving member when in driving position and cooperating therewith only when in normal or home position.
25. 3. In a device of the character described, the combination of a rotatable member, a driving member mounted thereon for rotary movement therewith and longitudinal movement thereof, and yielding means mounted on such rotatable member and acting on 30 said driving member to prevent creeping movement of the latter.
35. 4. In a device of the character described, the combination of a rotatable member, a driving member mounted thereon for rotary movement therewith and longitudinal movement thereof, and a light spring anchored at 40 one end to such rotatable member and adapted to engage said driving member with its free end.
45. 5. In a device of the character described, the combination of a rotatable screw-shaft, 45 a pinion screw-threaded thereon for rotary movement therewith and longitudinal movement thereof, and means mounted on the screw-shaft for preventing creeping movement of the pinion.
50. 6. In a device of the character described, the combination of a rotatable screw-shaft, a pinion screw-threaded thereon for rotary movement therewith and longitudinal movement thereof, and a spring at one end anchored to the screw-shaft and at its other 55 end loosely engaging the pinion.
55. 7. In a device of the character described, the combination of a rotatable screw-shaft, a pinion screw-threaded thereon for rotary movement therewith and longitudinal movement thereof, said pinion having a disk at one end, and a spring at one end anchored to the screw shaft and at its other end loosely engaging the periphery of said disk.
60. 8. In a device of the character described, the combination of a rotatable screw-shaft, a pinion screw-threaded thereon for rotary movement therewith and longitudinal move-

ment thereof, and a spring at one end anchored to the screw shaft and at its other end loosely engaging the pinion, said spring being bent reversely from its point of anchorage with its other or free end in the path of movement of the pinion.

65. 9. In a device of the character described, the combination of a rotatable screw-shaft, a pinion screw-threaded thereon for rotary movement therewith and longitudinal movement thereof, and a spring at one end anchored to the screw-shaft and at its other end loosely engaging the pinion, said spring being bent as to its body portion reversely from its point of anchorage with its outer 70 end portion bent at an angle to the body portion and into the path of movement of the pinion.

75. 10. In a device of the character described, the combination of a rotatable screw-shaft, a pinion screw-threaded thereon for rotary movement therewith and longitudinal movement thereof, and a spring at one end anchored to the screw-shaft and at its other end loosely engaging the pinion, said spring having its end formed at an angle, and said pinion having a disc which is engaged by 80 said angular end of the spring.

85. 11. In a device of the character described, the combination of a rotatable screw-shaft, a pinion screw-threaded thereon for rotary movement therewith and longitudinal movement thereof, and a spring at one end anchored to the screw-shaft and at its other end loosely engaging the pinion, said spring being in the form of a light wire bent reversely from its point of anchorage with its other or free end in the path of movement of the pinion.

90. 12. In a device of the character described, the combination of a rotatable screw-shaft, a pinion screw-threaded thereon for rotary movement therewith and longitudinal movement thereof, and a spring at one end anchored to the screw-shaft and at its other end loosely engaging the pinion, said spring being in the form of a light wire bent as to 95 its body portion reversely from its point of anchorage, with its outer end portion bent laterally at an angle to the body portion and with its extreme outer end bent obliquely upwardly and into the path of movement 100 of the pinion.

105. 13. In a device of the character described, the combination of a rotatable screw-shaft, a pinion screw-threaded thereon for rotary movement therewith and longitudinal movement thereof, and a spring at one end anchored to the screw-shaft and at its other end loosely engaging a part carried by the 110 pinion.

VINCENT BENDIX,
